UNITED STATES PATENT OFFICE.

BERNARDO ALBERGOLI, OF LAS ROSAS, ARGENTINA.

CONSTRUCTION OF WOODEN CHAIRS IN GENERAL.

1,357,673.

Specification of Letters Patent.

Patented Nov. 2, 1920.

Application filed May 4, 1917. Serial No. 166,373.

To all whom it may concern:

Be it known that I, BERNARDO ALBERGOLI, citizen of the United States, residing at Las Rosas, in the Province of Santa Fé and State of Argentine Republic, have invented certain new and useful Improvements in the Construction of Wooden Chairs in General, of which the following is a specification.

This invention relates to an improved wooden chair which can be constructed without the use of glue or other adhesives which are usually employed in the construction of articles of this character.

The principal objection to chairs in which the various parts are held together by glue is that such chairs, when exposed to weather are weakened or rendered entirely useless, due to the melting of the glue in the joints thereof. This objectionable feature is avoided, in accordance with the present invention, by joining the various parts of the chair by screws. Further, the said parts are so arranged that they strengthen or brace each other and present a construction of great strength and durability.

A further feature of the invention consists in making the seat of the chair of resilient wooden slats or strips. This construction is more durable than straw or cane and less expensive than leather, and has the important advantage that it is not affected by exposure to weather.

In the accompanying drawings, illustrating a preferred embodiment of the invention.

Figure 1 is a front view of the improved chair, in perspective,

Fig. 2 is a rear perspective view thereof,

Fig. 3 is a top view of part of the seat of the chair,

Fig. 4 is an underside view of the seat,

Fig. 5 is a sectional view of the seat,

Fig. 6 is a detail of the cross braces,

Figs. 7 and 8 are partial side elevations of one of the chair legs taken at right angles to each other.

The seat of the chair is formed by the frame 1 which is provided with a groove, wherein are fitted a number of strips of

wood 2 suitably spaced apart from each other. A number of strips of wood 3 extend transversely of the strips 2, and are suitably secured at their extremities to the frame 1, thus providing a flexible or resilient seat.

Two members 4 are screwed to the seat at 5, and have attached thereto legs 6 which extend upwardly, forming a back 7. The side pieces 8, which are integral with the legs 6, are connected at their upper ends by a cross-piece 9. A St. Andrews cross brace 10 is fixed within the frame of the back by means of screws 11. A similar cross brace 12 is provided between the front and rear legs on each side of the chair and is fixed to said legs by means of screws 13. A cross brace 14 is also provided between the rear legs 6, and the side crosses 12 are cross-braced as shown in Figs. 1 and 2 by means of a brace 16. The braces 14 and 16 are connected to the other members of the chair by suitable screws 15.

From the foregoing description it can readily be seen that the improved chair can be readily taken apart and re-assembled. The seat, the two side pieces and the cross brace between the latter can be laid flat upon the back piece, thus taking up comparatively little space for packing and transportation.

I claim—

A demountable wooden chair comprising uprights forming the frame of the back and the rear legs of the chair, front legs, side pieces between said front legs and said uprights, a seat frame detachably secured to said side pieces, wooden strips secured in recesses in said seat frame and spaced apart, resilient transversely extending strips of wood superposed above said spaced strips, whereby the resilient seat is obtained.

In testimony whereof I affix my signature in presence of two witnesses.

BERNARDO ALBERGOLI.
